(No Model.)

T. M. FELL.

FURNACE.

No. 288,416.

Patented Nov. 13, 1883.

UNITED STATES PATENT OFFICE.

THOMAS M. FELL, OF BROOKLYN, NEW YORK.

FURNACE.

SPECIFICATION forming part of Letters Patent No. 288,416, dated November 13, 1883.

Application filed June 14, 1883. (No model.)

To all whom it may concern:

Be it known that I, THOMAS MARA FELL, a citizen of the United States, residing at 320 Eighth street, in the city of Brooklyn, county of Kings, and State of New York, have invented an Improvement in Furnaces, of which the following is a specification.

My invention relates to the construction of the fire-boxes of locomotive engines and furnaces in which the fuel is fed to an auxiliary or front gas-furnace, delivering into a second or back combustion-furnace, the whole arranged and operated as one furnace; and the object of my invention is economy of fuel combustion and the prevention of smoke. I attain these objects by the mechanism illustrated in the accompanying drawings, in which—

Figure 1 is a vertical longitudinal section of all the parts; Fig. 2, a vertical cross-section of the front gas-chamber, and Fig. 3 a general plan.

Similar letters refer to similar parts throughout the several views.

A represents the front of auxiliary gas-furnace, B the combustion or back furnace, and C the boiler and tubes; *a* and *a l*, the usual water-ways; *b*, the ash-pit, having an air-door, *c*; *d*, the grate-bars, and *e* drop-bars; *f*, cleaning-door; *g*, a casing of iron surrounding the front or auxiliary gas-furnace, A, and having an opening or stoking-door, *h*, across the width of the grate-bars. This outer casing is bolted or fastened to the front water-way, *a*, (see Fig. 3,) and is arranged to hold or receive a lining of fire-brick, *i*, or other heat-resisting material on the front and both sides.

k represents the fuel-charging door or doors, having a number of fine holes for the admission of air, and which may be operated by a chain and pulley, as shown; *m*, a portable fire-back, extending horizontally across the entire width of the furnace and down and under the front wall or water-way, *a*, constructed with a number of fine holes, as seen in Figs. 1 and 3, for the purpose of delivering streams of hot air above the fuel and into the rear combustion-chamber, B. This fire-back, which I prefer made of what is known as "iron-stone," or of extra hard iron, is supported by the side

brick wall or lining, and when worn out can be easily removed and replaced by another back through the doors *k*.

n represents a line of small air-pipes entering through the water-way *a l*, and *o* an extension-plate to facilitate stoking. 55

It will be noticed (Fig. 1) that in order to operate this double arrangement of furnace from the front, and especially for stoking purposes through the door *h*, that the lower part 60 of the usual water leg or way, *a*, is much shortened, as seen by the dotted lines, and that the usual feed-door is dispensed with. The entire depth of both A and B need not exceed the usual or present dimensions of locomotive 65 fire-boxes.

The operation is as follows: The front chamber, A, is fed with fuel through the door *h*, and which should be kept charged above the space or distance between the grate-bars and the bottom of *m*. Air entering by the bars and the perforations on the door *h* produces the lower or first combustion of the fuel, (carbonic-oxide gas, &c.,) and on passing through the fuel or down and around to the combustion-chamber 70 B, and being highly heated, is ignited by the fresh supply of fine jets of air entering by the back *m* and the pipes *n*, and thereby producing the second or the higher combustion of the fuel-gases. Soft coal burned in 75 this furnace is kept in the chamber A until well coked, and in this condition is stoked back so as to cover the bars under the chamber B, and fresh fuel charged, as before stated. By keeping a thick bed of coal in the auxiliary 80 or front chamber, A, and a thin and bright fire in B, the most economical effect can be produced from any kind of fuel without smoke or the escape of combustible gas.

As modifications of my invention, the surrounding spaces occupied by the fire material *i* may be constructed to hold water; or such sides may be made part of the main shell of the boiler; and the perforations on the door *h* may be temporarily closed by an outer door or 90 plate, as seen in Fig. 2; but

What I claim as my invention, and desire to secure in this application, is—

1. In a locomotive fire-box or furnace having a front fuel-chamber, A, and a rear com- 100

bustion-chamber, B, the grate-bars *d*, extending under both said chambers, in combination with the feed and air door *h*, the lower or stoking door, *h*, and a fire-back, *m*, delivering streams of hot air into the rear combustion-chamber, B, all arranged and operating in the manner and for the purposes substantially described.

2. In furnaces, the portable fire-back *m*, con-

structed as described, in combination with a front fuel-chamber, A, a rear combustion-chamber, B, a feed-door, *k*, a stoking-door, *h*, and grate-bars *d*, all arranged and operating substantially as described.

THOMAS MARA FELL.
